UNITED STATES PATENT OFFICE.

ALBERT L. FULTON, OF SAN MATEO, AND THEODOR W. PETERSEN, OF SAN JOSÉ, CALIFORNIA.

BRICK-CARRIER.

SPECIFICATION forming part of Letters Patent No. 567,464, dated September 8, 1896.

Application filed December 11, 1895. Serial No. 571,805. (No model.)

To all whom it may concern:

Be it known that we, ALBERT L. FULTON, residing at San Mateo, in the county of San Mateo, and THEODOR W. PETERSEN, residing 5 at San José, in the county of Santa Clara, State of California, citizens of the United States, have invented certain new and useful Improvements in Brick-Carriers; and we do hereby declare that the following is a full, 10 clear, and exact description thereof.

Our invention relates to a receptacle for transporting bricks from the kiln to their destination, the object being to prevent the rehandling of the brick, with its expense, and 15 the loss of brick resulting from such rehandlings.

A further object is to insure an accurate tally of brick at the point of delivery, which is impossible under present conditions. Our 20 invention is particularly designed to be used in case the brick is manufactured at a distance from its point of delivery and is carried to such point by water in scows. In these cases the brick is loaded into barrows in the 25 kiln, then wheeled on board the scow and then stacked. At the end of the water-route the brick is again unloaded in barrows and dumped on shore and must then be placed in small carts, by which it is carried to its final 30 destination. There are three principal objections to this method of handling. First, each handling and rehandling is a source of expense, which can be roughly estimated at twenty-five cents per thousand brick; sec- 35 ondly, each handling causes a percentage of breakage, loss of bricks, and numerous worthless bats; thirdly, the tally at the point of delivery (for example, a building under construction) is never accurate, and only approximates the proper score of, say, five hundred brick to a cart-load. This error may be 40 accidental and caused by an inaccurate count at the cart, or it may be intentional. In either case there is complaint from the building-contractor.

Our invention enables the brick-manufacturer to load five hundred brick at the kiln, and deliver five hundred brick at their destination without intermediate handling and 45 without breakage, thus overcoming all the

objections above noted and materially reducing the cost of brick.

Our invention is illustrated in the drawings, in which—

Figure 1 is a bottom plan. Fig. 2 is a side 55 elevation. Fig. 3 is an end elevation.

A is a box which is designed to lie flat upon a platform-car, or to serve as a dumping-body upon a wheel-truck. To adapt it to these two purposes, its bottom boards 1 are supported by a framework composed of longitudinal and transverse beams or sills B and C. The outside beams, or all of them, if preferred, are faced with wearing-strips 2 of band-iron. The frame is preferably strengthened by tie-rods 3. The general shape of the box is rectangular, and it is composed of boards within and secured to a vertical side and end framing D E. Two of the iron straps which pass under the box are carried up the sides and 60 terminate in four hooks F, two on each side to receive hoisting-chains on a crane which 65 loads or unloads the boxes.

To the center transverse bottom beam C are secured the metallic plates 4. Formed 70 with these plates are curved bearings 5 and projections 6, each having an eye 7. It will be seen that these plates and their accessories are so placed, Fig. 2, that they do not project below the bottom framing, and hence the 75 whole box can lie flat upon the bottom beams. G is an ordinary tail-board which is set in guides 8 in the rear of the box-frame. We can, however, hinge one side of the box at the bottom and provide a simple spring-catch or 80 other fastening to secure its upper edge to the end frames. This makes the box as convenient to load at the kiln as an ordinary wheelbarrow. We may also hinge the tail-board at its upper edge. These modifications we 85 consider as forming parts of our invention. When the hinged side is used, the band-irons upon that side which have the hooks F will be separate pieces instead of extending under the box, as shown in Fig. 1.

In using this box it is placed upon a flat-car which is run into the kiln and is there loaded with the proper number of bricks to exactly fill it. That is, its capacity is gaged to, say, five hundred brick, which makes an 90 95 100

ordinary cart-load. The car, with its load of filled boxes, is then run to the scow, where the boxes are hoisted on board and stacked to the required load for the scow. At the end of 5 the water-route the boxes are hoisted upon shore and are ready for delivery at their destination. H represents any suitable wheel-truck, the bolster of which is provided with plates 9, having curved recesses 10, into which 10 the curved bearings 5 fit, and with projecting ears which engage the eyes 6, pins 11 being slipped through said ears and eyes to hold the parts in place. The box has now become a dumping-body, and, with its original load 15 as it left the kiln, is hauled to its destination and dumped, as shown in Fig. 2. The bricks have never been handled since first loaded at the kiln and, the capacity of the box being known, no intermediate tally of brick is required, but only a count of the number of 20 boxes. The empty boxes are shipped back to the kiln. There has been no chance for waste by breakage, because such breakage results from careless and frequent handling, which 25 we entirely avoid, and the industrial value of the invention may be summed up by a restatement of the facts before mentioned, that the cost of brick is decreased, the quality of brick delivered is improved by doing away 30 with the percentage of loss from breakage, while the count of brick is necessarily accurate, because each load is so easily checked by the builder or other consignee.

What we claim is—

1. A box or carrier for bricks having a bottom frame secured thereto, a plate secured thereto carrying one member of a hinge-joint said plate and hinge-joint carried thereby being confined above the plane of the edge of said bottom frame. 35

2. A box or carrier comprising the bottom and sides, the bottom frame secured to said bottom, the plate secured to said frame carrying one member of a hinge, the end of said member being turned upwardly between the 45 edge of said frame and the said bottom whereby said parts are confined above the plane of the edge of the bottom frame, substantially as described.

3. A combined receptacle and dumping- 50 body having a bottom and bottom frame, the hinged member carried thereby, the wheel-truck, and the corresponding hinge member carried by said truck, and a detachable connection between said members said connection being above the plane of the edge of said bottom frame. 55

In testimony whereof we have affixed our signatures, in presence of two witnesses, this 30th day of November, 1895.

ALBERT L. FULTON.
THEODOR W. PETERSEN.
